UNITED STATES PATENT OFFICE

162,409

OSCILLOGRAPH CASE

Claude M. Hathaway and Kurt E. Fox,
Denver, Colo.

Application December 21, 1950, Serial No. 13,528

Term of patent 14 years

(Cl. D26—5)

To all whom it may concern:

Be it known that we, Claude M. Hathaway, a citizen of the United States, residing at Denver, State of Colorado, and Kurt E. Fox, a citizen of the United States, residing at Denver, State of Colorado, have invented a new, original, and ornamental Design for an Oscillograph Case, of which the following is a specification, reference being had to the accompanying drawings, forming a part hereof.

Figure 1 is a perspective view showing the top; one side and one end; and

Figure 2 is a perspective view showing the top, the other side and the other end of an oscillograph case embodying our new design.

We claim:

The ornamental design for an oscillograph case, as shown.

CLAUDE M. HATHAWAY.
KURT E. FOX.
